LIGHTING FIXTURE

Walter W. Kantack, St. Albans, N. Y.

Application March 27, 1937, Serial No. 133,301

1 Claim. (Cl. 240—78)

This invention relates to lighting fixtures in general, the present application constituting a continuing application in part of my copending application for patent, Serial No. 9,356 filed 5 March 5, 1935, eventuating into Patent No. 2,075,206 on March 30, 1937.

Among the objects of the present invention, it is aimed to provide an improved lighting fixture or building fixture including a shell whose 10 cross-section is typical of a channel or trough and whose length is suitable for combination into an indefinite number of differently formed sections varying from a horizontally or vertically extending straight trough to a straight trough that 15 is inclined to the vertical, to a curved trough that is annular or not, to an irregularly shaped trough which engages and conforms to the outline of a particular wall face that may be vertical, horizontal or inclined to the vertical and to an independent 20 ornamenteally shaped trough without regard to the conformation or position of any wall face and without regard to its relation to any wall face, with a light source within the trough and light reflecting means to intercept light rays 25 from said source and redirect them onto the outer surface of said trough.

More generically, the invention relates to a combination including a light source, light source length or row of light sources and a fixture forming strip or length of a predetermined conformation having an outer design contributing conformation for concealing the light source or light sources and light reflecting means for intercepting direct light rays from said light source 30 or sources and redirect them onto the outer design contributing conformation of said strip or length.

These and other features, capabilities and advantages of the present invention will appear 40 from the subjoined detail description of specific embodiments thereof illustrated in the accompanying drawings in which

Figure 1 is a front elevation of a vertically extending strip having reflecting means on both 45 vertically extending edges for intercepting direct light rays from a source concealed by said strip and redirecting such light rays onto the outer face of such strip;

Fig. 2 is a transverse section on the line 2—2 50 of Fig. 1;

Fig. 3 is a front elevation of another form of vertically extending strip;

Fig. 4 is an enlarged transverse section on the line 4—4 of Fig. 3;

Fig. 5 is a fragmental section in perspective

still further enlarged of a portion of the shell of the strip shown in Fig. 4;

Fig. 6 is a perspective of a horizontally extending strip;

Fig. 7 is a fragmental bottom plan view of another embodiment having a closed end; 5

Fig. 8 is an enlarged transverse section on the line 8—8 of Fig. 7;

Fig. 9 is a fragmental bottom plan view illustrating a corner formed by two strips such as illustrated in Fig. 6; 10

Fig. 10 is a perspective of still another embodiment showing a curved strip formed into an annulus and suspended from a ceiling or the like;

Fig. 11 is an enlarged fragmental section on 15 the line 11—11 of Fig. 10;

Fig. 12 is a perspective of another embodiment showing a curved strip formed into an annulus and supported on a standard;

Fig. 13 is a bottom plan view of still another 20 embodiment showing a fixture preferably formed by two curved strips connected at their ends to resemble an ellipse;

Fig. 14 is a fragmental front elevation of a 25 pillar or the like with a strip in transverse section illustrated as extending around a portion of the pillar;

Fig. 15 is a fragmental transverse section of a 30 wall and strip secured thereto; and

Fig. 16 is a transverse section of still another 35 embodiment showing a fixture composed of a plurality of strips with reflecting means disposed to intercept light rays where the strips are spaced from one another.

In the embodiment illustrated in Figs. 1 and 2, there is shown a wall bracket 1 to which is connected a lamp 2, said wall bracket 1 having the arms 21 to which is connected the vertically extending shell 3 to conceal the lamp 2. The outer face of the shell 3 is preferably provided 40 with an ornamental effect either due to the configuration of the shell itself or to the ornamental matter secured thereto, Fig. 2 showing ornamental matter 4 secured to the outer face of the shell 3 in the present instance to form an 45 arrangement of raised and receding surfaces to intercept indirect light rays reflected by reflecting means formed along the vertically extending edges to the shell 3 to produce a predetermined ornamental effect consisting of light and 50 dark areas on the outer face of the shell 3.

The reflecting means in the present instance consists of the channels or channeled strips 5 which are positioned relative to the edges 6 of the shell 3 to intercept direct rays from the 55

lamp 2 with certain of its reflecting surfaces deflecting the light rays so received onto other reflecting surfaces all within the strips 5 which in turn deflect such received light rays onto the outer face of the shell 3.

From the foregoing, it will appear that the channels or channeled strips 5 are used to bring the light rays from the lamp 2 around the edges 6 onto the outer face of the shell 3.

10 For securing the channeled strips 5 in place in the present instance, there are provided two blocks 7 and 8 adjacent the lower end of the shell 3 and two blocks 9 and 10 adjacent the upper end of the shell 3, which blocks are slot-

15 ted to receive the end portions or edges 6 of the shell 3 and which blocks are also provided with outer faces conforming to the inner channeled surfaces of the strips 5 to snugly fit in the strips 5.

20 Preferably these blocks 7, 8, 9 and 10 are composed of a translucent substance or plastic material, such as "Catalin" to cooperate with the light rays of the lamp 2 to enhance the lighting effect according to the design which it

25 is desired to produce.

The shell 3 itself is preferably channeled or trough shaped to house the lamp 2 and conceal it from view. While the shell 3 is shown in the embodiments of Figs. 1 and 2 as intended for 30 use with a wall fixture, it may be spaced from the floor of the room in which it is located. It may of course also be supported on the floor as is the case with the vertically extending shell 11 in the embodiment illustrated in Fig. 3.

35 In the embodiment illustrated in Fig. 3, the shell 11 is sectional, the shell 11 being made sectional to facilitate manufacture with a design of the type there illustrated. The composite shell 11 there likewise is channeled or 40 trough shaped to house a lamp or source of light or row of lamps 12 and 13 and in the present instance is composed of two end sections 14 and 15, two intermediate sections 16, 17 and a peak section 18.

45 The sections 14 and 15 as shown are connected to the intermediate sections 16 and 17 respectively by the bayonet joints 19 and the sections 16 and 17 in turn are connected to the section 18 by the bayonet joints 20. The sections 16

50 and 17 in the present instance are provided with screw-threaded bosses 22 in alignment with openings in the flanges of the concave alzac reflecting shell 23 and also in alignment with openings in the ends of the arms 24 and 25 of the bracket 55 26 extending from the wall 27. There are provided as many brackets 26 as desired depending upon the height of the shell 11.

Secured to the reflecting shell 23 and extending inwardly therefrom, there are provided the tubes or conduits 28 to the inner ends of which are secured the sockets 29 for the lamps 12 and 13. The electrical conductors from the lamps 12 and 13 as shown in Fig. 4 extend from the sockets 29 out through the conduits 28 and then over and along the outer grooves 30 of the arms 24 and 25.

70 The upper edge of the shell may of course terminate in any ornamental design desired, preferably of course to correspond with the motif on the outer face of the shell 11. With a design, such as shown in Fig. 1, an intermediate round portion 31 may be preferred and with a design, such as shown in Fig. 3, probably the extension of the peak motif there shown may be preferred.

75 Along the lateral vertically extending edges

of the shell 11, there are arranged the reflecting means, in the present instance consisting of the strips 32 and 33 which may be connected to the shell 11 by any suitable means. In the present instance, screws 34 are shown extending from the inner overlapping portions of the strips 32 and 33 to the inner face of the outer edge formations 35. The strips 32 and 33 are preferably spaced from the edge formations 35 by the spacing collars 36 through which the screws 34 extend.

The number of lamps 12, 13 required for a shell 11 will of course depend upon the length of the same and upon the type of lamp used. In the embodiment illustrated in Fig. 3, there are shown two lamps of the standard filament type in which the axes of the sockets 29 extend vertically. The shells 11 in the present instance depend for their ornamentation upon the shape of the shell reflected in the outer appearance on the outer face of the same and also upon the particular surface finish provided. As an instance, the outer surfaces of the sections 14 and 15 have a plurality of projecting edges 37, the intermediate sections 16 and 17 a plurality of projecting edges 38 and the section 18 a plurality of projecting edges 39. These edges 37, 38 and 39 preferably have a smooth or plain finish as distinguished from a serrated or a saw tooth finish. The edges 37 in the present instance are the ends of smooth finished depressions 40 and 41 which are located within the path of light rays deflected by the inner faces of the reflectors or strips 32 and 33. The edges 38 on the other hand are narrow smooth finished strips 35 at the ends of intervening recesses 42 and 43 which have a serrated or saw tooth finish in cross-section, see Figs. 4 and 5.

The crests of the saw teeth characterizing the surface finish of the depressions 42 and 43 are parallel with the edges 38 to resemble a very finely ribbed surface. The depressions between successive teeth approximate one sixty-fourth of an inch in depth. Preferably the portion of the sections 14 and 15 adjacent the sections 16 and 17 are also recessed to form the concave recesses 44 which are also preferably provided with a serrated or saw tooth finish, such as the surface finish of the recesses 42 and 43.

The edges 39 as shown in Fig. 4 are preferably formed at the ends of ledges 45, 46 and 47. As indicated in Fig. 4, it will be apparent that at least the edges 37, 38 and 39 are in the path of the light rays deflected by the reflectors or strips 32 and 33. It will also appear that certain faces of the saw tooth finish of the surfaces 44, 42 and 43 will lie in the path of the light rays deflected by the reflectors or strips 32 and 33. The result will be that highly illuminated narrow stripes will be formed by the edges 37, 38 and 39. Surfaces of different light intensities and that will have different high light areas according to the location of the observer will be formed by the surfaces 44, 42 and 43 and dark areas formed between the sections 16, 17 and the ledges 45 and 46 and by the recesses formed between the ledges 45 and 46 and by the recesses formed between the ledges 46 and 47.

It is of course apparent that the serrated line defining the surfaces 44, 42 and 43 is not intended to portray the actual depth of a recess between successive saw teeth or successive ribs but rather merely to typify that these surfaces are not smooth and plane but serrated or saw tooth in cross-section.

The reflector 23 of course is provided mainly to reflect the light rays from the lamps 12 and 13 against the wall 27. In addition to the reflector 23, there are in the present instance provided two additional reflector shells 48 and 49 which are secured in the present instance to the inner faces of the sections 14 and 15 respectively.

Each reflector shell 48, 49 has a substantially plane portion 50 extending from an edge portion 35 inwardly substantially parallel to the light rays passing from the lamps 12, 13 to the reflectors or strips 32, 33. From the portion 50, each reflector 48, 49 is preferably as shown curved to form the portion 51 which extends toward and into engagement with the inner face of a section 14, 15 near its bayonet joint 19. These reflectors 48, 49 are preferably secured to the sections 14, 15 respectively by screws, such as the screw 52, in the present instance connecting the curved portion 51 to a section 14, 15 adjacent its bayonet joint 19.

In the embodiment illustrated in Fig. 6, there is shown a channeled shell 53 similar to the shell 11 but extending horizontal as an instance from one pillar 54 to another, not shown. In this embodiment, the shell 53 is shown as composed of three sections, two sections 55 and 56 substantially identical to one another in place of the sections 14, 16 and 15, 17 respectively, and a third section 57 in place of the section 18. Here each section 55, 56 has only two smooth finished stripes 58 and 59 defining the intervening edges by the three concave successive depressions 60, 61 and 62, each of which has a surface finish that is preferably serrated or saw tooth in cross-section, such as the saw tooth surface of the recesses 44, 42 and 43 of Fig. 4.

The section 57 is preferably connected to the sections 55 and 56 by bayonet joints 63 and 64 similar to the bayonet joints 20 and otherwise substantially identical in shape and surface finish to that of the section 18 in Fig. 4.

Along the longitudinal outer edge portions 65 and 66, there are provided the channeled reflecting strips 67 and 68, similar to the reflecting strips 32, 33 of the embodiment shown in Fig. 4 and also positioned to intercept direct light rays from a lamp 69 or similar lamp source mounted inside of the shell 53 and deflect them onto other surfaces within the channels 67 and 68 in turn to be deflected onto the outer faces of the shell 53 again to produce a plurality of brightly illuminated stripes with intervening dark areas and light changing areas, such as those produced by the serrated surfaces 60, 61 and 62.

The light source may be mounted within the shell 53 in any suitable way, in the present instance, if lamps such as the standard filament lamps are used by connecting the lamps 69 to sockets 70 connected to projections 71, 72 extending inwardly from the inner faces of the sections 55, 56. In some instances, the shell 53 may of course be solely supported at its ends by pillars such as the pillar 54. On the other hand, as illustrated in the embodiment of Figs. 7 and 8, such a shell, as an instance the shell 73 may be connected to one or more ceiling brackets 74 extending down from the ceiling 75. The brackets 74 may be similar to the brackets 26 of the embodiment illustrated in Fig. 4 having a tubular portion 76 to which are connected the arms 77, 78 connected at the lower ends to projections 79, 80 extending inwardly from the inner faces of the sections 81 and 82 of the shell 73.

75 Here too, preferably a concave reflecting shell

83 is connected between the ends of the arms 77, 78 and the projections 79, 80, respectively. In this embodiment, similarly, the sections 81 and 82 are provided with bent reflecting means 84, such as the shells 48, 49 illustrated in the 85 embodiment of Fig. 4.

In this embodiment the ends of the shell 73 may be closed as particularly indicated in Fig. 7 by rounding the sections 81, 82 into one another at the ends of the shell 73. The reflecting strips 10 85 and 86 along the outer edge portions of the sections 81, 82 are similarly rounded into one another as indicated at 87. For the purpose of finish, the edges 88 of the section 89 are also rounded into one another at one end of the shell 15 73 as at 90.

As distinguished from the embodiment illustrated in Fig. 6 in which the reflecting strips 67 and 68 may be supported at their ends by the pillars, such as the pillar 54, other supporting 20 means will have to be provided in the embodiment of Fig. 8 for the reflecting strips 85, 86. These reflecting strips 85, 86 may here also be connected to the outer ends of the sections 81 and 82 by the screws 91.

25 Any number of other ways may of course be provided for closing the ends of the shells 73 depending upon the ornamental finish required.

In the embodiment of Fig. 9 as an instance, it is shown how a plurality of these shells 73 may 30 be connected together to form an angle with one another in turn to form a completely enclosed polygonally shaped shell or only part of a polygon as when connected to a pillar extending from a corner of a room. As clearly shown in Fig. 9, 33 when the angle desired is a right angle, it is only necessary to cut two shells, such as the shells 92 and 93 to form an angle of forty-five degrees at 94 with the longitudinally extending sides of the shells when such shells 92 and 93 40 may be connected together as indicated in Fig. 9.

The reflecting strips 95, 96 and 97, 98 will of course similarly be cut to cooperate with one another to form the right angular configuration shown in Fig. 9.

45 In the embodiment shown in Fig. 10, advantage is taken of this channeled or trough shaped shell to produce the annulus 99. The annulus 99 shown in Fig. 10 is illustrated as secured to three ceiling brackets 109, 101 and 102. The lower end portion 103 of the annulus 99 is similar to the ledge formation of the section 18 illustrated in Fig. 4. Here the outer faces of the annulus 99 above the portion 103 is illustrated as provided with a raised ornamentation 104 resembling a garland, see Fig. 11.

55 In the embodiment illustrated in Fig. 12, an annulus 105 composed of the channeled or trough shaped shell, such as the shell 53 of Fig. 6 is shown secured to a plurality of arms 106, 107 and 108 of a standard 109. In this case, it is of course obvious that the reflecting rim or strip 110 at least on the outer periphery of the trough shaped shell 105 may be directly connected to the arms 106, 107 and 108.

65 Fig. 13 illustrates how advantage may be taken of this trough shaped shell to form an elliptical configuration where preferably two curved trough shaped shells 111 and 112 are connected to one another at their ends 113 and 114 as indicated.

70 In the embodiment illustrated in Fig. 14, it is illustrated how advantage may be taken of a half of a trough shaped shell, such as the shell 115 which is longer in a horizontal direction than 75

it is wide in a vertical direction, to encircle a pillar 116 constituting a structural or building element. In this embodiment the shell 115 has the edges of the lower circular wall portion 118 engaging the cylindrical surface or face of the pillar 116 to form a closed bottom continuing into a lateral cone shaped wall portion 119 having shoulders formed thereon ornamenteally arranged to define a desired design when intercepting reflected light rays from the reflecting rim or strip 120 similar to the reflectors or strips 32 and 33 of Fig. 3 which intercept light rays from a light source, such as the lamp 121 and reflect such light rays as indirect light rays onto said shoulders.

In the embodiment illustrated in Fig. 15, there is illustrated how advantage is taken of a half of a channeled shell to produce the generic effect here desired to be produced when a straight shell, such as the channel shaped shell 122 is secured along the side of a wall. In the present instance, the shell 122 has an inner wall portion 123 connected to the building wall 124, a lower wall portion 125 secured to the shoulder or ledge 126 constituting a portion of the building wall 124 and an outwardly flaring curved wall portion 127 having an outer face provided with shoulders ornamenteally arranged to intercept light rays reflected by the reflector or strip 128 which is supported along the outer edge of the wall portion 127 and which intercepts direct light rays from a light source between the wall portions 123 and 127, such as the lamp 129.

In the embodiment illustrated in Fig. 16, it is illustrated how advantage may be taken of the trough shaped shell typified by the shell 23 of Fig. 6 to produce a lighting fixture having a plurality of reflecting strips combined with a plurality of outer shells whereby the outer faces of the shells are illuminated by reflected light rays reflected by the reflecting strips of direct light rays produced by a light source disposed within the shells.

In this embodiment, the channel shaped main shell 130 comprises two walls 131 and 132, in the present instance merging into one another at their lower end 133. Here too, the walls 131 and 132 are shown as having secured to their outer faces ornamental or decorative shoulder forming material, such as the portions 135, 136, 137 and 138 which have shoulders in the path of the light rays reflected by the reflecting strips 139 and 140 which receive direct light rays from a source of light within the trough formed by the shell 130, one lamp 141 here being shown.

The fixture here shown is illustrative of a ceiling fixture in which advantage is taken of the brackets for the lamps for support, the lamp 141 as an instance being secured to the socket 142 and mounted in the socket cover 143 connected to the ceiling, not shown, and the socket cover 143 is connected to the brackets 144 by any suitable means, such as the flexible chains 145. The brackets 144 are in the present instance connected to the blocks 243 which are slotted to receive the outer edges of the walls 131 and 132 and otherwise conformed snugly to fit in the channeled strips 139 and 140.

In the present instance, the strips 139 and 140 are shown as integral with the outwardly flaring trough forming walls 146 and 147 extending outwardly and upwardly from said strips 139 and 140.

The outer faces of the walls 146 and 147 are also provided with an ornamental covering substance, such as the portions 148 and 149 which have shoulders to intercept light rays deflected by the inner faces of the reflecting strips 150 and 151 which receive and intercept direct light rays from the lamp 141 and reflect them as indirect light rays onto the outer faces and ornamental portions of the walls 146 and 147 as well as parts of the shell 130.

The reflecting strips 150 and 151 are supported in place by being mounted on blocks 152 preferably composed of some translucent material, such as "Catailin." These blocks 152 are conformed to snugly fit into the channels of the channeled strips 139 and 140. These blocks 152 are furthermore slotted to receive the outer edges of the walls 146 and 147.

It is obvious that various changes and modifications may be made to the details of construction without departing from the general spirit of the invention as set forth in the appended claim.

I claim:

In a building, a vertically extending pillar, a shell extending around said pillar and engaging the face thereof at its lower end to form a closed bottom and extending outwardly therefrom in an upward direction to form a long narrow trough with the face of the pillar, a plurality of lamps in the trough and out of view from the outside of said shell, and reflecting means supported on the edge of the shell and positioned outwardly from the outer edge thereof to receive and intercept direct light rays from said lamps and deflect them as indirect light rays onto the outer face of said shell.

WALTER W. KANTACK. 55
